UNITED STATES PATENT OFFICE.

JOZEF LATOSZEWSKI, OF PLYMOUTH, PENNSYLVANIA.

MINE-CAR STOP.

Application filed March 7, 1925. Serial No. 13,743.

To all whom it may concern:

Be it known that I, JOZEF LATOSZEWSKI, a citizen of Poland, residing at Plymouth, in the county of Luzerne and State of Pennsylvania, have invented certain new and useful Improvements in Mine-Car Stops, of which the following is a specification.

This invention relates to certain new and useful improvements in mine car stops, and has for its primary object to provide a device that is disposed at one side of a mine car track and to be operated automatically by a mine car for projecting a brake shoe or block between the spokes of the mine car wheel for braking the mine car and bringing the same to rest.

A further object of the invention is to provide a mine car stop that is automatically operated by having a movable part thereof arranged in the path of travel of a mine car and wherein a chock block or brake shoe carried by a shiftable bar is thrown between the spokes of the mine car wheel.

With the above and other objects in view that will become apparent during the course of the following description, the same consists of the novel form, combination and arrangement of parts hereinafter more fully described, shown in the accompanying drawing and claimed.

In the drawing, wherein like reference characters designate corresponding parts throughout the several views,

Figure 1 is a side elevational view of the mine car stop constructed in accordance with the present invention, the mine rail with which the device is associated being shown in section.

Figure 2 is a top plan view of the device showing the same set in its operative position by full lines with the operating arm therefore illustrated in dotted lines in its shifted position.

Figure 3 is a side elevational view, similar to Fig. 1 showing the position assumed by the several parts of the device after operation thereof with the chock block or brake shoe between the spokes of the mine car wheel, and

Figure 4 is a vertical cross-sectional view taken on line IV—IV of Fig. 1.

Referring more in detail to the accompanying drawing, there is illustrated a mine car stop embodying a base plate 1 of elongated

formation as illustrated in Fig. 2 and carrying clips or anchoring devices 2 upon one end thereof that engage beneath the mine car rails 3 for anchoring the same in position.

Pairs of vertical posts 4 project perpendicularly from the base plate 1, the posts 4 being disposed at the outer end of the base plate, while the posts 5 are disposed intermediate the ends thereof and are of greater height than the end posts 4. A pair of guide bars 6 having forwardly inclined upper sides 7 are disposed between adjacent posts 4 and 5 while a forwardly inclined bar 8 extends between the upper ends of the pairs of posts 4 and 5 and projects forwardly of the post 5 with the ends thereof terminating adjacent the inner end of the base plate 1 and spaced upwardly therefrom as illustrated in Figs. 1 and 3. Another bar 9 extends between the posts 4 and 5 intermediate the upper and lower ends thereof and has a forward extension 10 projecting forwardly of the intermediate post 5, the bars 9 and 10 being forwardly and upwardly inclined with the upper inclined end of the bar section 10 lying in a plane parallel with the upper inclined sides 7 of the bars 6.

The rod 11 is slidably mounted between the pairs of perpendicular posts 4 and 5, between the side bars 6 and beneath the inclined bar 9 and carries adjacent the forward end thereof a closed link 12 that encloses the bar 10 with the upper end of the link 12 freely slidable upon the upper inclined face of the bar 10. A horizontal arm 13 is carried by the upper side of the rod 11 and projects laterally thereof for riding upon the upper inclined face 7 of one of the side bars 6. It will therefore be seen that when the rod 11 is shifted in a direction toward the rail 3, the link 12 and arm 13 will elevate the rods and maintain the same in a horizontal position as illustrated in Fig. 3.

The operating means for the rod 11 includes the slotting of the forward end of the upper bar 8 to provide upper and lower arms 14 between which a lever 15 is pivotally mounted upon the pin 16 at the outer ends of the arms 14. The inner end of the lever 15 is spaced from the end of the slot and a pulley 17 is rotatably mounted upon the pin 18 between the inner ends of the

arms 14. Another pulley 19 is journaled in an opening 20 provided in one of the intermediate posts 5 that is alined with the outer end of the arm 13 as shown in Figs. 5 2 and 4 and a cable or cord 21 secured at one end to the outer end of the arm 13 passes over the pulleys 19 and 17 for attachment to the inner end of the lever 15. As shown more clearly in Fig. 3, guides 22 are carried 10 by the post 5 and bar 6 for directing movement of the cable 21. The outer end of the lever 15 carries a head 23 that is pivotally mounted thereon as at 24 as shown in Figs. 1 and 2 so that upon shifting movement of 15 the head 23, the apparatus may be rendered either operative or inoperative for contacting by a part of the mine car C.

A chock block or shoe 25 of the form best 20 illustrated in Figs. 1 and 3 has one pointed end thereof positioned in the notched outer end 26 of the rod 11 while the forward end 27 of the lock 25 is provided with a cushioned surface to prevent injury to the spokes of the mine car wheel. When the 25 rod 11 is retracted as illustrated in Fig. 1, the block 25 is supported at its inner end by the notched end of the rod 11 while the outer end thereof rests upon the support 28.

With the device positioned as illustrated 30 in Fig. 1, and with the head 23 extended, a mine car approaching the apparatus will have an appropriate part there adapted for contacting the head 23 for moving the lever 15 upon its pivot 16, the cable connection 21 between the inner end of the lever 15 and the arm 13 carried by the rod 11 will cause the rod 11 to be moved to the position shown in Fig. 3 for throwing the chock block 25 between the spokes of the mine car wheel, the rod 11 being elevated as illustrated by the link connection 12 between said rod and the bar 10 and also by reason of the fact that the arm 13 rides upwardly upon the inclined upper face 13 of the side bar 6. 40 When it is desired to render the apparatus inoperative, the head 23 is shifted upon its pivotal mounting 24 to displace the same out of the path of movement of the mine car.

50 While there is herein shown and described the preferred embodiment of the present invention, it is nevertheless to be understood that minor changes may be made therein

without departing from the spirit and scope of the invention as claimed.

What is claimed is:—

1. In a mine car stop, a frame structure associated with a mine car rail, a rod slidably associated with the frame structure, a brake shoe shiftable between the spokes of 60 a car wheel upon movement of the rod and means operated by a mine car and connected to the rod for shifting the same.

2. In a mine car stop, a frame structure associated with a mine car rail, a rod slidably associated with the frame structure, a brake shoe shiftable between the spokes of a car wheel upon movement of the rod, means operated by a mine car and connected to the rod for shifting the same, and means associated with the rod for raising the same 70 during shifting movement.

3. In a mine car stop, a frame structure associated with a mine car rail, a rod slidably associated with the frame structure, a 75 brake shoe shiftable between the spokes of a car wheel upon movement of the rod, a lever pivoted on the frame structure, a cable connecting the lever to the rod, and means carried by the lever adapted to be placed 80 in the path of movement of a mine car.

4. In a mine car stop, a frame structure associated with a mine car rail, a rod slidably associated with the frame structure, a brake shoe shiftable between the spokes of 85 a car wheel upon movement of the rod, a lever pivoted on the frame structure, a cable connecting the lever to the rod, and a head pivotally mounted at the outer end of the lever adapted to be placed in the path of 90 movement of a mine car.

5. In a mine car stop, a frame structure associated with a mine car rail, a rod slidably associated with the frame structure, a brake shoe shiftable between the spokes of 95 a car wheel upon movement of the rod, means operated by a mine car and connected to the rod for shifting the same, said frame structure including a pair of vertically spaced inclined bars and links carried by 100 the rod associated with the bars for elevating the rod during shifting movement.

In testimony whereof I affix my signature.

JOZEF LATOSZEWSKI.
